TUNING DEVICE FOR RADIO RECEIVERS OR
THE LIKE

William H. Grinditch, Rydal, John M. Bowman, Philadelphia, and Leo B. Glaser, Drexel Hill, Pa., assignors to Philco Radio and Television Corporation, Philadelphia, Pa., a corporation of Delaware

Application April 23, 1937, Serial No. 138,642

17 Claims. (Cl. 250—20)

This invention relates to tuning devices for radio receivers or the like and, more particularly, to a novel tuning device which is simple in construction and economic to manufacture and assemble, and which embodies the several novel features described hereinafter.

One object of the invention is to provide a novel radio tuning device by means of which a radio receiver may be tuned readily to a desired broadcasting station by the simple process of moving a rotatable member into cooperative relation with a selected one of a plurality of stop elements, to thereby adjust the tuning element or elements of the receiver rapidly and easily to a position corresponding to the position of the selected stop element, whereby the radio receiver is tuned to a particular station represented by the said stop element. More specifically, the device comprises a stationary support carrying a plurality of selectable elements which are annularly arranged and adapted to be selectively engaged by a rotatable member to thus adjust or position the tuning element or elements of the radio receiver. The rotatable member carries an axially movable member which is maintained in one of three positions. In one of these positions, it is interlocked with one of the several stops.

Another object of the invention is to provide a tuning device in which the tuning knob moves annularly around the tuning dial, and in which the dial mechanism is located behind the face of the dial but can be easily and quickly adjusted from the front of the cabinet.

Still another object of the invention is to provide a device of the character above mentioned wherein the said selectable elements are individually adjustable in a simple manner from the front of the radio cabinet to cause the said elements to correspond respectively to different broadcasting stations. More particularly, the said selectable elements are mounted on an annular track and are so constructed that they may be loosened or tightened by means of a tool inserted from the front of the radio cabinet to enable adjustment of the said elements along the said track.

A further object of the invention is to provide a device of the stated character wherein the above-mentioned axially movable member is provided with an axial opening through which a tool may be inserted to loosen or tighten the stop elements as above mentioned.

A further object of the invention is to provide a radio tuning device of the stated character wherein the above-mentioned axially movable

member controls switching means for rendering the radio receiver operative or inoperative depending upon the particular axial position of the said member. In one of the axial positions of said member, the switching means renders the radio receiver operative so that the tuning adjustment may be made by ear. In the other positions of the said member and while the member is being manipulated to tune the radio receiver rapidly by means of the stop elements as above mentioned, the switching means renders the radio receiver inoperative until the desired station is properly tuned in. The device is so constructed that if a desired station is not properly tuned in, the switching means maintains the radio receiver inoperative.

A further object of the invention is to provide a vernier knob carried by the said member and adapted to frictionally engage a stationary annular frictional surface to permit fine adjustment by rotating the said vernier knob about its axis.

Other objects and features of the invention will be apparent hereinafter. In the accompanying drawings:

Fig. 1 is a front view of the tuning device mounted in a radio cabinet;

Fig. 2 is a bottom plan view of the same;

Fig. 3 is a sectional view of the mechanism separated from the cabinet, taken along line 3—3 of Fig. 1, showing the axially movable member in cooperative engagement with a selected stop element;

Fig. 4 is an enlarged sectional view taken through the axially movable member as disclosed in Fig. 3 and showing the elements associated with said member;

Fig. 4A is a sectional view of an adjusting tool;

Fig. 4B is an end view of the tool;

Fig. 5 is a fragmentary sectional view showing the axially movable member in another of its positions;

Fig. 6 is a similar view showing the axially movable member in still another position;

Fig. 7 is a diagrammatic illustration of the switch circuit and showing the connection thereof to a radio receiver;

Fig. 8 is a face view of the stationary supporting member carrying the stop elements; and

Fig. 9 is a fragmentary sectional view taken along line 9—9 of Fig. 3.

Referring particularly to Figs. 1 to 3, there is provided a supporting member or plate 1 which is adapted to be mounted on a radio chassis within a radio cabinet in proper relation to the front panel 1a of the cabinet. The plate 1 carries a

50

55

plurality of annularly arranged stop elements 2, the construction and purpose of which will be described in detail later. A rotatable shaft 3 extends through plate 1 as shown in Fig. 3 and is supported by a bearing block 4 attached to the plate 1. The shaft 3 is connected to the tuning elements or condensers of the radio receiver or to suitable driving means therefor, preferably by means of a flexible coupling 5. It will be understood, therefore, that rotation of shaft 3 serves to actuate the tuning element or elements of the radio receiver to tune the receiver to a desired station.

The block 4 carries a housing 6 within which there is mounted a stationary translucent dial 7 having graduations and indicia thereon as shown in Fig. 1, indicating the frequency to which the set may be tuned and the location of some of the various broadcasting stations on the dial. On the end of shaft 3, there is provided a pointer 8 which moves with the shaft adjacent the face of the dial. A transparent cover or face plate 9 is secured to the housing 6 by means of a mounting ring 10 which has a front annular serrated or beaded surface 11, the purpose of which will be described later. One or more light sources 12 are mounted within the housing to eliminate the translucent dial 7.

A crank arm 13 is attached to the rotatable shaft 3 so that the shaft may be rotated by rotating the crank arm. At its outer end, the arm 13 has an angularly extending arm portion 14 which carries a hollow support or boss 15, as shown more clearly in Figs. 4 to 6. A tubular or hollow member 16, which will be described in detail later, is slidably and rotatably carried by the support 15 and is provided with a knob 17 by means of which it may be moved axially or moved bodily to turn the crank arm 13 and thus rotate shaft 3. The member 16 has three axial positions, viz., an outer position, an intermediate position, and an inner position. The manner in which the device functions when member 16 is positioned in each of its three positions will be clearly understood later.

Referring now to Fig. 8, the supporting plate 1 is provided with an annular track 19 which is formed by two concentric flanged rings 20 and 21 having the cross-sectional shape shown in Fig. 4. Each of the stop elements 2 has a conical head 22 and a threaded shank 23 adapted to extend between the rails of track 19. A nut 24, which seats snugly between the rail members, serves to hold the stop element in place on the track. The rails of the track are cut away, as shown at 25 in Fig. 8, in order that the stop elements with the nuts attached thereto may be inserted and moved into place on the track. The recess 25 is of such size and shape that it permits the nut 24 to be inserted and then moved behind the flanges of rails 20 and 21. The nut 24 may be squared and the recess 25 may likewise be square as shown. Since the nut of each stop element is held against rotation by the track rails, the stop elements may be loosened or tightened by turning their conical heads, and in this manner the stop elements may be adjusted to different positions along the annular track. To enable adjustment of the stop elements in this manner from the front of the device, the conical head of each stop element is provided with two opposed recesses 26 which are adapted to receive the forked end of a special tool provided for the purpose of adjustment. A tool comprising a rod 78 having its end cut out to provide two male mem-

bers adapted to interlock with the recesses 26 in any one of the stop elements may be used to loosen or tighten the stop elements to permit adjustment thereof. Such a simple tool is shown in Figs. 4A and 4B.

The inner end of the axially movable member 16 has an internal conical surface 27 (see Fig. 6) which is adapted to fit over and snugly engage the conical head of any one of the stop elements. When the member 16 is moved to its inner position above mentioned, it may engage the head of a selected stop element in the manner shown in Fig. 4. The member 16 not only serves cooperatively with the conical heads of the stop elements to accurately adjust the tuning element 15 or elements of the radio receiver, but also serves to position the stop elements during adjustment thereof. To this end, the hollow member 16 is adapted to receive the tool above mentioned, the tool being inserted longitudinally through the member 16 and brought into engagement with a selected stop element. When the stop element has been loosened by means of the tool in this manner, the member 16 may be moved to move the stop element to the desired position as determined by the aural reception of the radio receiver. For example, if it is desired to move one of the stop elements to a position corresponding to a particular station, the member 16 in the axial position shown in Fig. 4 is moved, carrying the stop element with it until the radio receiver is tuned to the particular station. The stop element is then tightened in place on the track 19 by means of the tool as above described. Thereafter, the particular stop element serves cooperatively with the member 16 in the rapid tuning operation of the device.

Adjacent the knob 17, there is provided on member 16 a slidable and rotatable disk 28 (see Fig. 4) to which there is secured a small collar 29 formed of frictional material such as leather or rubber. The disk 28, which serves as a vernier knob as described below, is urged outward against knob 17 by means of a spring 18. The spring is relatively weak and serves only to hold the vernier knob 28 away from the frictional surface 11. It has no effect upon the positioning of the member 16 which is held in any one of its several axis positions by means described hereinafter. By moving the disk 28 inwardly against the action of spring 18, the collar 29 may be caused to engage the serrated surface 11, as may be seen from Fig. 3. The purpose of this structure is two fold. As described hereinafter, in the intermediate position of the member 16, fine adjustment of the tuning of the radio receiver by ear may be effected by rotating the disk 28 while holding it inwardly with the collar 29 against the surface 11. The frictional engagement between the surface 11 and the collar 29 causes the collar 29 to ride along the annular surface 11, thus moving the member 16 and rotating crank arm 13. During this method of tuning, the radio receiver is operative so that it may be tuned by ear in the usual manner. In addition to this function, however, the cooperative frictional surfaces enable fine adjustment of any one of the stop elements 2. When one of the stop elements is adjusted in the manner above described, instead of moving the member 16 by means of its knob 17, the adjustment may be made by pressing the disk 28 inwardly and rotating it to cause slow movement of member 16 by means of the frictional surfaces. There

is thus provided a vernier tuning control and adjustment device.

The tuning device is adapted to be mounted in a suitable cabinet having a circular opening in its front face 1a, as shown in Figs. 1 and 2. The dial housing 6 may extend into the opening so that the face plate 9 is flush with or projects slightly beyond the face of the cabinet. The tuning knob shaft 16, which carries the tuning knob, also extends through the opening in the cabinet which must be large enough to permit this shaft to rotate about the dial housing 6, as described above. To close the opening between the housing and the cabinet face there is provided an annular movable bezel or ring 29a which is carried by the crank arm housing 15, as shown in Figs. 2 and 9. The use of this movable bezel not only improves the appearance of the device but also permits the locating of the stop mechanisms behind the front of the cabinet in a semi-concealed and relatively inaccessible position. While means are provided for easy adjustment of the stop mechanism, accidental and injurious contact with them is thus made difficult. As shown in Fig. 2, a felt ring 29b may be carried by the bezel 29a to close the small space between the bezel 29a and the stationary bezel 29c on the cabinet, and to exclude light.

In further accordance with the invention, there is provided switching means for rendering the radio receiver operative or inoperative for different axial positions of the member 16. To this end, there is provided on the supporting plate 1, an electrically conductive ring 30 which is insulated from the supporting plate by means of the insulating ring 31 (see Figs. 3, 5, 6 and 8). The ring 30 forms one contact of a switch 32, while a spring arm 33 constitutes the other element of this switch. The spring arm 33 carries a contact button 34 which normally engages the ring 30 by virtue of the resilience of the arm 33. The spring arm 33 is carried by crank arm 13 but is insulated therefrom by means of insulating washers 35. A conductor 36 is connected to ring 30, while a second conductor 37 is connected to the spring arm 33. The further connection of conductor 36 will be described later. Conductor 37 has its opposite end connected to a contact button 38 (see Fig. 9) which is carried by an insulating plunger 49 slidably disposed in a transverse opening or recess provided in the wall of the hollow structure 15. The plunger 39 is urged toward member 16 by means of a coil spring 40 and the spring-operated plunger assembly is adjustably held by means of the screw plug 41. The contact button 38, together with the member 16, constitutes a switch, as described further herein-after, which is connected in series relation with the switch 32.

The angular extension 14 of arm 13 is provided with a recess 42 (see Figs. 4 to 6) within which there is carried a transverse pin 43 on which there is mounted a pawl 44 which is adapted to actuate the spring arm 33 to open switch 32. The pawl 44 is provided with an elongated slot 45 within which the pin 43 is slidably disposed. Thus, the pawl is pivotally mounted on pin 43 and is adapted for bodily movement thereon. A spring 46 urges the pawl 44 to inoperative position and normally maintains the pawl in such position, as shown in Fig. 5. When the member 16 is moved to its inner position, its inner end engages the nose 47 of the pawl and causes pivotal movement of the pawl about the pin 43. If the member 16 is not in cooperative relation with

one of the stop elements, the pawl is moved pivotally only, the pin 43 remaining in the end of slot 45 as shown in Fig. 5. In such case, the pawl does not engage the spring arm 33. If the member 16 is in cooperative relation with one of the stop elements, however, as shown in Fig. 6, it (member 16) moves the nose 47 of the pawl into engagement with the conical head of the stop element, and the conical surface of the stop element serves as a cam to move the pawl into engagement with the spring arm 33. In other words, the pivotal movement of the pawl caused by member 16 and the simultaneous cam action of the plunger head on the pawl, together cause the pawl to move to the position shown in Fig. 4, 15 the pin 43 riding to the opposite end of slot 45. This causes the nose 48 of the pawl to engage the end of spring arm 33 and to move the spring arm to the position shown in Fig. 3, thus opening the switch 32. As will be more clearly understood 20 later, the switch 32 determines whether the radio receiver is operative or inoperative when the member 16 is in its inner axial position. It will be noted that the switch is opened only when the member 16 is moved into cooperative relation with 25 one of the stop elements and, therefore, the receiver is rendered operative only if a desired station is tuned in by means of a selected stop and the member 16. If, through inadvertence, the member 16 is not aligned with a selected stop 30 element so that the inner end of member 16 does not properly engage the conical head of the stop element, the switch 32 is not opened and, therefore, the radio receiver is maintained inoperative. It will be seen, therefore, that the person tuning 35 the radio receiver will know at once that he has not located the member 16 in proper relation to the stop element.

The member 16 comprises two interfitting and interlocked metallic sleeves 49 and 50 which are 40 arranged as clearly illustrated in Fig. 4. An insulating collar 51 is mounted on the sleeve 49 between a flange 52 thereof and the end of sleeve 50. The sleeve 49 is provided with annular recesses 53, 54 and 55 which are selectively engageable by a spring-pressed plunger 56 (see Fig. 9) to maintain the member 16 in any one of its three positions. The plunger 56, together with its associated spring 57, is held in a transverse opening in the wall of the hollow support 15 by means of an adjustable screw plug 58. In the outer position of member 16, as shown in Fig. 9, the spring-pressed plunger 56 seats in the annular recess 55. As the member 16 is moved inwardly axially, the spring-pressed plunger seats successively in the recesses 54 and 53. Thus, the member 16 is snapped into any one of its three positions and is held in position by the detent mechanism.

When the member 16 is in its outer position, 60 as shown in Fig. 9, the contact button 38 engages the metallic surface of member 16 on the left side of the insulating collar 51 as viewed in the figure. When the member 16 is moved to its intermediate position, the contact button 38 65 engages the insulating collar 51. When the member 16 is moved to its inner position, the contact button 38 engages the metallic surface of member 16 on the right side of the insulating collar 51. In this manner, the axial movement 70 of member 16 effects a switching action which, together with switch 32, determines whether the radio receiver is operative or inoperative.

Referring now to Fig. 7, there is shown a portion 59 of the audio frequency channel of a con- 75

ventional radio receiver employing a volume control device 60 in the form of a potentiometer having a movable contact 61. The conductor 36 which is connected to ring 30 as above mentioned 5 may be connected to the movable arm of the volume control device as illustrated. The metallic portions of member 16, which is shown diagrammatically in Fig. 7, are grounded through the metallic parts of the tuning device since the device is mounted on the radio receiver chassis. This grounding of the metallic portions of member 16 is illustrated diagrammatically in Fig. 7 at 62. It will now be seen from Fig. 7 that the switch 32, together with the switch formed by member 15 16 and the contact button 38, are connected in series in a circuit extending from the volume control device 60 to ground. When both of the switching devices are closed so that the ground circuit is completed, the radio receiver is rendered 20 inoperative. If either of the switching devices is open, however, the ground circuit is open and the radio receiver is rendered operative.

From the above description, it will be seen that when the member 16 is in its outer position, the 25 two switching devices are closed and the radio receiver is rendered inoperative. At this time, the member 16 is free of the stop elements and it may be rotated to bring it in line with any one of the stop elements (as determined by the pointer 30 8 and the dial indicia) and then pressed to its inner position into engagement with the stop element. If the selected stop element is properly engaged by member 16, the switch 32 is opened as above described, thus opening the ground circuit and 35 rendering the radio receiver operative. As pointed out above, however, if the member 16 is not in proper relation with the stop element, the switch 32 remains closed so that the radio receiver remains inoperative. It will be noted that the inward movement of member 16 will cause the contact button 38 to move over the insulating collar 51, thus opening the ground circuit momentarily but the contact button 38 will immediately move onto the metallic surface of member 16 to the 40 right of collar 51, thus closing the ground circuit. When the member 16 is moved axially to its intermediate position, the contact button 38 engages the insulating collar 51 as shown in Fig. 7, thus opening the ground circuit and rendering the 45 radio receiver operative. With the member 16 in this axial position, the radio receiver may be tuned by ear by pressing disk 28 inwardly and rotating the disk to effect fine adjustment as described above.

In order to maintain the rotatable parts in an 50 adjusted position during the fine tuning operation which does not make use of the stop elements, there is provided a counterbalancing weight 63 which counterbalances the weight of arm 13 and the elements carried thereby. While the weight 63 is shown attached to a part of the coupling 5, it will be apparent that it may be applied to any part of the rotatable structure.

It will be apparent that the device is simple 55 in construction so that it may be manufactured and assembled economically and it embodies the several novel features above described. While a preferred form of the device has been illustrated for the purpose of disclosure, it will be understood that the invention is not thus limited but is capable of various modifications within the scope of the appended claims.

We claim:

1. In a tuning device for a radio receiver or the 60 like, stationary supporting means, a plurality of

annularly arranged selectable elements carried by said supporting means and adapted for annular adjustment relative to one another, each of said selectable elements having a projecting head, a rotatable shaft for rotating a tuning element of 5 said receiver, a crank arm carried by said shaft, and an axially movable member carried by said arm and adapted to selectively engage one of said elements to stop said tuning element at a predetermined position corresponding to the position 10 of the selected element, said member having an axial opening therethrough terminating in a recess for receiving the head of the selected element and permitting insertion of a tool through said opening for adjustment of said elements. 15

2. In a tuning device for a radio receiver or the like, stationary supporting means, a plurality of 20 annularly arranged selectable elements carried by said supporting means and adapted for annular adjustment relative to one another, each of said 25 selectable elements having a projecting conical head, a rotatable shaft for rotating a tuning element of said receiver, a crank arm carried by said shaft, an axially movable member carried by said arm and adapted to selectively engage one of said 30 elements to stop said tuning element at a predetermined position corresponding to the position of the selected element, said member having an axial opening therethrough terminating in a conical recess for receiving the conical head of the selected element and permitting insertion of a tool through said opening for adjustment of said elements, and means for holding said member in engagement with the selected element. 35

3. In a tuning device for a radio receiver or the like, stationary supporting means, a plurality of 40 selectable elements carried by said supporting means, means for adjusting a tuning element of said receiver including a member movable axially to three positions, means actuatable by said member in one of its axial positions for adjusting said tuning element, said member in another of its axial positions adapted to be moved into alignment with a selected one of said elements to adjust 45 said tuning element, said member in its third axial position adapted to engage the selected element, and switching means for rendering said receiver inoperative when said member is in said second-mentioned position, and for rendering said receiver operative when said member is in its other 50 two positions.

4. In a tuning device for a radio receiver or the like, stationary supporting means, a plurality of 55 selectable elements carried by said supporting means, means for adjusting a tuning element of said receiver including a member movable axially to three positions, means actuatable by said member in one of its axial positions for adjusting said tuning element, said member in another of its axial positions adapted to be moved into alignment with a selected one of said elements to adjust 60 said tuning element, said member in its third axial position adapted to engage the selected element, and switching means controlled by said member for rendering said receiver inoperative 65 when said member is in said second-mentioned position or when said member is in its third position but not in proper engagement with a selected element, and for rendering said receiver operative when said member is in said first- 70 mentioned position or when said member is in its said third position in proper engagement with a selected element.

5. In a tuning device for a radio receiver or the like, stationary supporting means, a plurality 75

- of selectable elements carried by said supporting means, means for adjusting a tuning element of said receiver including a member movable axially to three positions, means actuatable by said member in one of its axial positions for adjusting said tuning element, said member in another of its axial positions adapted to be moved into alignment with a selected one of said elements to adjust said tuning element, said member in its third axial position adapted to engage the selected element, a normally closed switch operable by said member in its said third axial position, and switching means open when said member is in its first-mentioned position and closed when said member is in its other two positions, said switch and said switching means being serially connected and adapted for connection to said receiver to render it inoperative when both said switch and said switching means are closed.
6. In a tuning device for a radio receiver or the like, stationary supporting means, a plurality of selectable elements carried by said supporting means, means for adjusting a tuning element of said receiver including a member movable axially to three positions, means actuatable by said member in one of its axial positions for adjusting said tuning element, said member in another of its axial positions adapted to be moved into alignment with a selected one of said elements to adjust said tuning element, said member in its third axial position adapted to engage the selected element, a normally closed switch, a pawl arranged for actuation by said member and adapted to open said switch only when said member is in proper engagement with a selected element, and switching means open when said member is in its first-mentioned position and closed when said member is in its other two positions, said switch and said switching means being serially connected and adapted for connection to said receiver to render it inoperative when both said switch and said switching means are closed.
7. In a tuning device for a radio receiver or the like, stationary supporting means, a plurality of selectable elements carried by said supporting means, means for adjusting a tuning element of said receiver including a member movable axially to three positions, means actuatable by said member in one of its axial positions for adjusting said tuning element, said member in another of its axial positions adapted to be moved into alignment with a selected one of said elements to adjust said tuning element, said member in its third axial position adapted to engage the selected element, a normally closed switch, a pawl arranged for actuation by said member and a selected element when said member moves into proper engagement with said element, to thus open said switch only when said member is in proper engagement with said element, and switching means open when said member is in its first-mentioned position and closed when said member is in its other two positions, said switch and said switching means being serially connected and adapted for connection to said receiver to render it inoperative when both said switch and said switching means are closed.
8. In a radio receiver, a cabinet having an opening in the front face thereof, a tuning dial structure disposed within said opening, a plurality of stop elements disposed within said cabinet, means including a member extending into said opening and movable therein about said dial structure for tuning said receiver, an axially movable member carried by said first member and

adapted to engage a selected one of said stop elements, and a bezel carried by said first member and serving to substantially close the opening around said dial structure.

9. In a tuning device for a radio receiver or the like, stationary supporting means, a plurality of selectable elements carried by said supporting means and adapted for adjustment relative to one another, and a manually movable member for actuating a tuning element of said receiver and adapted to selectively engage one of said elements to stop said tuning element at a predetermined position corresponding to the position of the selected element, said member having an opening therethrough for insertion of a tool to adjust said elements, whereby said elements may be disposed inaccessibly normally but may be adjusted by the said tool.

10. In a tuning device for a radio receiver or the like, stationary supporting means, a plurality of annularly arranged selectable elements carried by said supporting means and adapted for annular adjustment relative to one another, each of said selectable elements having a projecting head with spaced recesses for receiving a tool, a rotatable shaft for rotating a tuning element of said receiver, a crank arm carried by said shaft, and an axially movable member carried by said arm and adapted to selectively engage one of said elements to stop said tuning element at a predetermined position corresponding to the position of the selected element, said member having an axial opening there through terminating in a recess for receiving the head of the selected element and permitting insertion of said tool through said opening for adjustment of said elements.

11. In a tuning device for a radio receiver or the like, stationary supporting means, a plurality of selectable elements carried by said supporting means, a manually rotatable and axially movable member for rotating a tuning element of said receiver and adapted to selectively engage one of said elements to stop said tuning element at a predetermined position corresponding to the position of the selected element, a stationary member having an annular frictional surface, a friction member carried by and movable axially along said first member into engagement with said surface to effect fine tuning adjustment, and means for maintaining said friction member normally out of engagement with said surface.

12. In a tuning device for a radio receiver or the like, stationary supporting means, a plurality of selectable elements carried by said supporting means, a manually rotatable and axially movable member for rotating a tuning element of said receiver and adapted to selectively engage one of said elements to stop said tuning element at a predetermined position corresponding to the position of the selected element, a stationary member having an annular frictional surface, and a friction member carried by and movable axially along said first member into engagement with said surface to effect fine tuning adjustment.

13. In a radio apparatus, a cabinet having an opening in the front face thereof, a tuning dial structure disposed within said opening, a plurality of stop elements disposed within said cabinet behind the front face thereof, a rotatable arm behind said dial structure for actuating a tuning element of the apparatus, an axially movable member carried by said arm and extending outward through said opening adjacent the edge of the dial, for selectively engaging any one of said

stop elements, whereby said member may be moved about the dial into alignment with a selected stop element and then moved axially to engage the said element, and a bezel carried by said arm and serving to conceal the space between the dial structure and the edge of the cabinet opening, whereby said stop elements, said arm and the rear portion of said member are at all times concealed from view.

14. In a radio apparatus, a cabinet having an opening in the front face thereof, a tuning dial structure disposed within said opening, a plurality of stop elements disposed within said cabinet behind the front face thereof, a rotatable arm behind said dial structure for actuating a tuning element of the apparatus, an axially movable member carried by said arm and extending outward through said opening adjacent the edge of the dial, for selectively engaging any one of said stop elements, whereby said member may be moved about the dial into alignment with a selected stop element and then moved axially to engage the said element, a bezel carried by said arm and serving to conceal the space between the dial structure and the edge of the cabinet opening, whereby said stop elements, said arm and the rear portion of said member are at all times concealed from view, a stationary member having an annular frictional surface adjacent said bezel, and a friction member carried by and movable axially along said first member into engagement with said surface to effect fine tuning adjustment.

15. In a radio apparatus, a cabinet having an opening in the front face thereof, a tuning dial structure disposed within said opening, a plurality of adjustable stop elements disposed within said cabinet behind the front face thereof, a rotatable arm behind said dial structure for actuating a tuning element of the apparatus, an axially movable member carried by said arm and extending outward through said opening adjacent

the edge of the dial, for selectively engaging any one of said stop elements, whereby said member may be moved about the dial into alignment with a selected stop element and then moved axially to engage the said element, a bezel carried by said arm and serving to conceal the space between the dial structure and the edge of the cabinet opening, whereby said stop elements, said arm and the rear portion of said member are at all times concealed from view, said member having an axial opening therethrough for insertion of a tool to adjust said stop elements, a stationary member having an annular frictional surface adjacent said bezel, and a friction member carried by and movable axially along said first member into engagement with said surface to effect fine tuning adjustment.

16. In a tuning device for a radio receiver or the like, a plurality of selectable elements, a member constructed and arranged for rotation and for movement in a direction substantially perpendicular to the plane of rotation to selectively engage one of said elements to thereby effect tuning adjustment, a stationary member having an annular frictional surface, and a friction member carried by said first member and movable therealong in said direction into engagement with said surface to effect fine tuning adjustment.

17. In a tuning device for a radio receiver or the like, a plurality of selectable elements, a manually rotatable and axially movable member adapted to selectively engage one of said elements to thereby effect tuning adjustment, a stationary member having an annular frictional surface, and a friction member carried by and movable axially along said first member into engagement with said surface to effect fine tuning adjustment.
